DESIGN FOR A CLOTHES CLIP

Frank Coogler, Washington, D. C., and John C. Coogler, Houston, Tex.

Application May 7, 1945, Serial No. 119,436

Term of patent 14 years

(Cl. D17—6)

To all whom it may concern:

Be it known that we, Frank Coogler, a citizen of the United States, residing in the city of Washington, District of Columbia, and John C. Coogler, a citizen of the United States, residing in the city of Houston, county of Harris, State of Texas, have invented a new, original, and ornamental Design for a Clothes Clip, of which the following is a specification, reference being had to the accompanying drawing, forming a part thereof.

In the drawing:

Fig. 1 is a front view of a clothes clip showing our new design.

Fig. 2 is a side view thereof.

Fig. 3 is a top plan view thereof.

We claim:

The ornamental design for a clothes clip, substantially as shown.

FRANK COOGLER.
JOHN C. COOGLER.
